UNITED STATES PATENT OFFICE.

GEORGE HEATH ROBINSON, OF LONDON, ENGLAND, ASSIGNOR TO THE CARTER-CRUME COMPANY, LIMITED, OF TORONTO, CANADA, A CORPORATION.

LOOSE-LEAF BINDER.

964,811.

Specification of Letters Patent. Patented July 19, 1910.

Application filed April 28, 1908. Serial No. 429,594.

To all whom it may concern:

Be it known that I, GEORGE HEATH ROBINSON, a subject of the King of Great Britain, residing at Crouch End, London, 5 England, have invented a certain new and useful Improvement in Loose-Leaf Binders, of which the following is a full, clear, and exact description, such as will enable others skilled in the art to which it appertains to 10 make and use the same.

This invention relates broadly to devices known as temporary or loose leaf binders, but in a more intense aspect it proposes a self-contained device having a series of posts 15 rigidly rising from an inner face of a cover thereof, and so devised that a plurality of loose leaves may be accumulated thereon and, when desired, be removed *en bloc* therefrom, while at the same time drawing a 20 binding cord through the apertures in a manner enabling a permanent binding to be obtained by a simple tying operation.

This invention accordingly has in view, among other objects, a loose leaf binder 25 which may be conveniently used as a means for receiving and retaining an accumulation of sheets, and in which the free ends of one or more of the fixed binding posts may be releasably engaged with a removable cover, 30 and in which certain of said ends are also adapted for taking hold of a binding cord whereby it may be properly drawn through the apertures when the sheets are removed 35 *en bloc* from said binder so that the free ends of the cord will be in a condition for tying to permanently bind the sheets together.

In general, the object of this invention 40 is to devise a temporary binder of the nature disclosed which, from the standpoint of practical usage, will be possessed of a high degree of serviceability and ease of operation, and which, structurally considered, will be of the greatest possible simplicity 45 and strength, being composed of but few parts, all of which are so formed as to be capable of being manufactured at a low cost.

Other parts will be in part obvious from 50 the annexed drawings and in part pointed out hereinafter.

In order that this invention may be the more readily understood, drawings illustrating one of the many possible forms 55 thereof are appended as a part of this dis-

closure, and as will be readily perceived by those skilled in the art, other modified forms will be immediately apparent or easily deducible from this disclosure, and accordingly are to be regarded as being within 60 the intended scope of the annexed claims. In such drawings like characters of reference denote corresponding parts throughout all the views of which:—

Figure 1 is a perspective view of a loose 65 leaf binder embodying my invention, the parts being shown in their opened-out relation preparatory for threading a binding cord through the free ends of the fixed posts of the binder. Fig. 2 is a view somewhat similar to Fig. 1, but showing the set 70 of accumulated leaves removed *en bloc* from the binder, and illustrating the manner in which the binding cord is handled by the above named posts. 75

Continuing now by way of a more detailed description, with such occasional reference to the drawings as may be conducive to a clear comprehension of this invention, A indicates a suitable holder for the leaves. 80 Each holder comprises an intermediate section or back 1 to the longitudinal edges of which are hinged, or otherwise flexibly secured, a pair of covers 2 and 3. It will, of course, be understood that one of these covers 85 may be regarded as the top cover, and the other as the bottom cover, as the case may be, and in accordance with good practice these covers may be made relatively stiff and faced with good wearing material. On one of these covers, as for example, from the cover indicated by 3, I have arranged a plurality of guides or binding posts, which posts are solid and rigidly secured to such 90 cover and rise or spring therefrom in alignment with and adjacent its line of hinge with the back 1. While I do not assign any particular number of posts as being absolutely essential to the series of posts contemplated by my invention, it may nevertheless be observed that I ordinarily prefer to 95 use three equi-spaced posts, as shown by the drawings. I have not only employed these posts as a convenient means for receiving from time to time and retaining together in 100 book-like form a plurality of sheets, but I have also so formed these fixed posts that they may, on the one hand, serve to detachably retain the opposite cover in place, and, 105 on the other hand, constitute a means in-

strumental in conveniently threading the binding cord through the apertures of the leaves when the latter are removed *en bloc*, so that it only remains for the operator to pass one of the cord-ends through the intermediate loop and then tie the ends together to form a neatly bound bundle of papers. To these ends, I have provided the posts with means for detachably engaging with the opposite cover, and also with means such as hooks and eyelets for taking hold of the binding cord and drawing the same through the apertures in the leaves. Thus, the two end posts 4 and 5 have their upper extremities provided with loops or eyelets 6 and 7, respectively, and also provided with annular recesses or necks 8 and 9, whose function is to engage with a digitally operated interlocking means on the opposite flap or cover 2. The intermediate post 10, which preferably is arranged equi-distant from the two above-mentioned posts, also rises rigidly from the flap or cover 3, and at its upper end provides a means for easily grasping and releasing an intermediate portion of a cord to be employed for binding purposes. For this purpose, the upper extremity of the intermediate post 10 is preferably provided with a hook 11, which, as will be perceived, is not only capable of easily taking hold of a middle portion of the binding cord, but equally permits of an immediate disengagement when such cord has been drawn through into the relation shown by Fig. 2. It will, of course, be perceived that in lieu of the closed eyelets 6 and 7 in the end posts of the series, hooks or other retaining expedients may be adopted, but from many aspects the eyelet is the better form, inasmuch as it is inherently strong and the free ends of the cord may be readily withdrawn therefrom when in the position indicated by Fig. 2.

B denotes a series of marginally apertured leaves which are from time to time built up or accumulated on the above-mentioned guiding or binding posts, preparatory to being finally removed *en bloc* in registry. To facilitate this latter operation, I have devised a registering device which consists of an elongated bar 12 having apertures 13, 14 and 15 for receiving the posts 4, 10 and 5 respectively. Rigidly secured to such apertured bar 12, preferably midway between each pair of apertures, I have arranged posts 16 and 17, which posts are adapted for being inserted into the corresponding apertures provided by the leaves of the set B for the purpose of retaining the same in registry during removal. As will be seen, when this has been done, these posts pass through wholly, or in a large part, through the set of leaves and form a registry insuring means, thereby promoting and facilitating the withdrawing of such leaves

en masse from the binding or guide posts 4, 10 and 5. The binding cord, which previously has been secured to the binding posts, will now have been drawn through the apertures in the set of leaves, so that it only remains to tie the free ends of said cord together, having first passed one or more of such ends through the middle loop, which will have been disengaged from the hook 11 on the middle post 10.

To enable the binder to be more conveniently used from day to day when it is receiving its accumulation of leaves, I have devised a simple means of detachably holding the covers together through the instrumentality of the end posts 4 and 5. This means forms a gripping device D arranged on the cover or flap 2. This device comprises an elongated plate 18 which is slidably mounted in such cover, as by means of a top plate 19. An upturned element 20 of the elongated plate 18 protrudes at the end of the same, and provides a finger piece, thereby enabling the elongated plate to be digitally positioned to be engaged or disengaged, as the case may be, with the binding posts. This latter operation may be accomplished through the enlarged head receiving apertures 21 having narrow slots 22 extending therefrom in the sliding plate 18. The overlying plate will also have an entering aperture 23. Now, the extremities of the binding posts may be inserted through the apertures 23 in the cover plate, then into the apertures 21 in the sliding plate 18, and, by longitudinally translating such plate 18 by means of the finger grip 20, the neck will enter the elongated slots which will securely hold the same in place against withdrawal. A spring 24 may also be used as a means of retaining the sliding plate in its locking position.

It will thus be perceived that I have devised a binder well adapted to achieve the several objects and ends of my invention. The device as a whole is simple, compact and serviceable, and moreover, requires a minimum amount of manipulation or dexterity on the part of the operator. By using the solid binding posts also as a means for threading the leaves together with binding cord, I have succeeded in obtaining a very strong and effective construction in a particular which otherwise would be characterized by the essential and inherent structural weakness.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be

understood that the language used in the following claims is intended to cover all of the generic and specific features of the invention herein described and all statements of the scope of the invention which, as a matter of language, might be said to fall therebetween.

Having described my invention, what I claim as new and desire to secure by Letters 10 Patent is:

1. In a loose leaf binder, in combination, a pair of covers, a plurality of posts rigidly secured to one of said covers, certain of said posts having their free ends provided with 15 means for temporarily retaining a binding cord, a sliding member mounted in said other cover having a plurality of apertures formed therein, the cord retaining means of one or more of said posts being provided 20 with portions adapted to engage a similar number of apertures in said sliding member.

2. A loose-leaf binder comprising in combination, a cover, a plurality of posts secured thereto and spaced apart along a margin 25 thereof, certain of said posts being eyeleted to receive a binding cord, and another post being provided with a hooked end for temporarily retaining an intermediate portion of a binding cord adapted to be drawn 30 through perforations in a series of leaves assembled on said posts when said leaves are removed.

3. A loose-leaf binder comprising in combination, a holder having a pair of complementary top and bottom covers, a back to which said covers are hinged, a spaced series 35 of binding posts rigidly secured to one of said covers adjacent its hinge line, certain of the posts of said series having their free 40 ends provided with means for temporarily retaining a binding cord, another post of said series having its free end forming a hook for detachably engaging an intermediate portion of said binding cord, and 45 means for interlocking the other cover with one or more of the free ends of said posts.

4. A loose-leaf binder comprising in combination, a holder having a pair of top and bottom covers, a back to which said covers 50 are hinged, a spaced series of binding posts rigidly secured to one of said covers adjacent its hinge line, the outer posts of said series having their free ends provided with eyelets adapted to receive a binding cord, an intermediate post of said series having its free 55 end forming a hook for detachably engaging an intermediate portion of said binding cord, an elongated plate slidably mounted in said opposite cover adjacent the hinge line thereof and having one or more apertures, 60 one or more of the posts of said series having necked heads adapted to interlock with said

apertures, and means for digitally sliding said plate to engage or disengage said posts therefrom.

5. A loose-leaf binder comprising in combination, a holder having a pair of complementary top and bottom covers, a back to which said covers are hinged, a spaced series 65 of binding posts rigidly secured to one of said covers adjacent its hinge line, certain of the posts of said series having their free ends provided with means for temporarily retaining a binding cord, another post of said series having its free end forming a hook for detachably engaging an intermediate portion of said binding cord, and an elongated bar having apertures adapted 70 to receive certain of the posts of said series and provided with one or more posts rigidly secured thereto and adapted to be inserted in corresponding apertures in a set of sheets to maintain them in registry during removal from said binding posts.

6. A loose-leaf binder comprising in combination, a holder having a pair of complementary top and bottom covers, a back to which said covers are hinged, a spaced series 75 of binding posts rigidly secured to one of said covers adjacent its hinge line, the outer 80 posts of said series having their free ends provided with eyelets adapted to receive a binding cord, an intermediate post of said series having its free end in the form of a hook adapted to detachably engage an intermediate portion of said binding cord, and an elongated bar having a series of 85 apertures for receiving certain of the posts of said series and provided with one or more posts rigidly secured thereto, and adapted 90 to be inserted in corresponding apertures in a set of sheets to maintain them in registry 95 during removal from said binding posts.

7. A loose leaf binder comprising, in combination, a pair of covers, a plurality of 100 posts rigidly secured to one of said covers certain of said posts having their free ends provided with means for temporarily retaining a binding cord, and a sliding member 105 mounted in said other cover and having a plurality of apertures formed therein, one or more of said posts being provided with reduced portions adapted to engage the apertures in said sliding member, the reduced portion of each post being positioned 110 between its extreme free end and its associated cord-retaining means.

In testimony whereof I affix my signature in the presence of two witnesses.

GEORGE HEATH ROBINSON.

Witnesses:

ALLEN PARRY JONES,
EDWARD T. FOSTER.

It is hereby certified that in Letters Patent No. 964,811, granted July 19, 1910, upon the application of George Heath Robinson, of London, England, for an improvement in "Loose-Leaf Binders," an error appears in the printed specification requiring correction, as follows: Page 1, line 49, the word "parts" should read *objects*; and that the said Letters Patent should be read with this correction therein that the same may conform to the record of the case in the Patent Office.

Signed and sealed this 30th day of August, A. D., 1910.

[SEAL.]

F. A. TENNANT,

Acting Commissioner of Patents.
